UNITED STATES PATENT OFFICE.

JAMES J. SMALL, OF FAIRFAX, MISSOURI.

RAILWAY-GATE.

1,209,056.

Specification of Letters Patent. Patented Dec. 19, 1916.

Application filed October 5, 1915. Serial No. 54,184.

To all whom it may concern:

Be it known that I, JAMES J. SMALL, a citizen of the United States, residing at Fairfax, in the county of Atchison and State of Missouri, have invented certain new and useful Improvements in Railway-Gates, of which the following is a specification.

This invention relates to railway gates, and more particularly to gates of this type which are designed to prevent stock from getting on the track.

The invention has for its object to provide a novel and improved gate of the kind stated which is normally closed and which is automatically opened by a train approaching the same, and is held open while the train is passing, after which it is again closed.

The object stated is attained by means of a combination and arrangement of parts to be hereinafter described and claimed, and in order that the same may be better understood reference is had to the accompanying drawings, in which—

25 Figure 1 is a plan view of the invention; Figs. 2 and 3 are longitudinal sections on the lines 2—2 and 3—3, respectively, of Fig. 1, and Fig. 4 is a cross-section on the line 4—4 of Fig. 1.

30 Referring specifically to the drawings, 5 denotes the rails of a railroad track, the same being mounted on cross ties or stringers 6 in the ordinary manner. At the place along the track where a cattle guard is necessary or desirable, is mounted a double gate, the two members of which are indicated at 7, the same being mounted respectively, on opposite sides of the track and so dimensioned and positioned that they swing 35 transversely of the track, and meet at the middle thereof when in closed position. It will be understood, of course, that a single gate or door, reaching across the track, may be employed with equal facility.

40 Each gate 7 is fastened at its inner end to an upright post 8 which is rotatable and stepped at its lower end in a cross sill 10 extending beneath the track. The top of the post is journaled in a bearing 11 carried 45 by an upright 12 rising from the sill 10 and suitably braced. The gate may also be formed integral with the post.

The gates 7 are normally closed and they thus prevent cattle from getting on the 50 track. In order that the gates may be automatically opened to permit the passage of

trains over the track, the following mechanism is provided: On opposite sides of the gate 7, some distance therefrom, are mounted rollers 13 located beneath the rails and 60 extending transversely of the track. The rollers are journaled in suitable bearings 14. On the ends of the rollers are wound cables 15 extending along the track and connected intermediate their ends to the pivot posts 8 65 of the gates by being wound around the same. To the rollers 13 are fixed tappet arms 16 which are located between the track rails 5, and are normally upstanding so as to be in the path of the pilot of the locomotive. The rollers are connected by longitudinal bars 17 positioned along the inner side of the track rails, in proximity thereto, and at such an elevation that they are in the path of the flanges of the car wheels. The 70 connection between the rollers and the ends of the bars is made by means of staples 18 carried by the rollers, and eyes 19 at the ends of the bars, through which the staples loosely pass. This provides a loose connection between the rollers and the bars. To each roller is also fastened, and partly wound, a cable 20 having connected to its free end a coiled spring 21 which is anchored to one of the ties 6. The springs 21 85 are for the purpose of turning the rollers in a direction to restore the tappet arms to upright position, and for closing the gate.

The gate-operating mechanism works as follows: The gates 7 are normally closed, 90 they being held in this position by the springs 21 and the connections between the rollers 13 and the gate pivot posts 8. The tappet arms 16 are also normally in upright position, in which position they rise to a 95 sufficient height to be struck by the pilot of an approaching locomotive. When the pilot strikes the tappet arm on that side of the gate from which the train is approaching, the roller 13 to which said tappet arm is connected turns in a direction to unwind the cables 15 thereon, the cables winding on the other distant roller, the latter being turned by the connecting bars 17. By this operation of the cables, the pivot posts are rotated 100 in a direction to swing the gates open. The gates are held open until the entire train has passed the same, as the wheel flanges ride over the bars 17 and hold the same depressed, thereby preventing the rollers 110 from turning to close the gates. When the last pair of wheels leaves the bars 17, the

latter are free to rise, and the springs 21 then restore the parts to their normal position, the gates being swung back to closed position.

g The operation hereinbefore described is entirely automatic and controlled by the passing train. The gates are opened by a train approaching in either direction.

By employing a gate normally closed and 10 extending as a barrier across the track, it is not necessary to equip the track with the usual cattle guards.

I claim:—

1. The combination of a railway gate pivoted to swing across the track, a vertical pivot carrying the gate, transverse rotary elements positioned beneath the track on opposite sides of the gate, a connection between said elements and the gates for swinging the latter, tappets on the rotary elements and projecting above the track when the gate is closed, longitudinal bars connecting the rotary elements and extending along the

inner sides of the track rails in proximity thereto to be engaged by the wheel flanges, 25 and closing means for the gate.

2. The combination of a railway gate pivoted to swing across the track, a vertical pivot carrying the gate, transverse rollers mounted beneath the track on opposite sides 30 of the gate, a cable wound on said rollers and wound intermediate its ends around the gate pivot, tappets on the rollers, and projecting above the track when the gate is closed, longitudinal bars connecting the rollers and extending along the inner sides of the track rails in proximity thereto to be engaged by the wheel flanges, and closing means for the gate.

In testimony whereof I affix my signature 40 in presence of two witnesses.

JAMES J. SMALL.
